CLAIM

The ornamental design for an appliquéd set, as shown and described.

DESCRIPTION

FIG. 1 is a top plan view of an appliquéd set, showing my new design;

FIG. 2 is an elevational view of several individual appliqués shown removed from the set of FIG. 1 and affixed to the front surface of a portable computer;

FIG. 3 is an elevational view of several different individual appliqués shown removed from the set of FIG. 1 and affixed to the rear surface of the portable computer; and,
FIG. 4 is a side elevational view thereof.

FIGS. 2-4 are shown at a reduced scale. The bottom surface of the appliquéd set is not part of the claimed design. The relative thickness of the appliquéd set is as shown in FIG. 4. The broken line illustration of the portable computer shown in FIGS. 2-4 is for illustrative purposes and forms no part of the claimed design.
